[57] **CLAIM**

The ornamental design for a cobblestone, substantially as shown and described.

DESCRIPTION

FIG. 1 is a perspective view of a cobblestone showing my new design;
FIG. 2 is a top plan view thereof;
FIG. 3 is a side elevational view thereof, which also accurately represents the opposite side plan view;

FIG. 4 is a side elevational view, which also accurately represents the opposite side plan view thereof;
FIG. 5 is a bottom plan view thereof;
FIG. 6 is a perspective view of a first alternate embodiment of my new design;
FIG. 7 is a top plan view thereof;
FIG. 8 is a side elevational view, which also accurately represents all other sides thereof;
FIG. 9 is a bottom plan view thereof;
FIG. 10 is a perspective view of a second embodiment of my new design;
FIG. 11 is a top plan view thereof;
FIG. 12 is a side elevational view, which also accurately represents the opposite side plan view thereof;
FIG. 13 is a side elevational view, which also accurately represents the opposite side plan view thereof;
FIG. 14 is a bottom plan view thereof;
FIG. 15 is a perspective view of a third embodiment of my new design;
FIG. 16 is a top plan view thereof;
FIG. 17 is a side elevational view, which also accurately represents the opposite side plan view thereof;
FIG. 18 is a side elevational view, which also accurately represents the opposite side plan view thereof;
FIG. 19 is a bottom plan view thereof;
FIG. 20 is a perspective view of a fourth embodiment of my new design;
FIG. 21 is a top plan view thereof;
FIG. 22 is a side elevational view, which also accurately represents the opposite side plan view thereof;
FIG. 23 is a bottom plan view thereof;
FIG. 24 is a perspective view of a fifth embodiment of my new design;
FIG. 25 is a top plan view thereof;
FIG. 26 is a side elevational view, which also accurately represents the opposite side plan view thereof;
FIG. 27 is a side elevational view, which also accurately represents the opposite side plan view thereof;
FIG. 28 is a bottom plan view thereof.
